NUMERICAL PRINTING DEVICE

Willem Gerhard Brill, Johannesburg, Transvaal,
Union of South AfricaApplication December 30, 1936, Serial No. 118,355
In Great Britain June 22, 1936

8 Claims. (Cl. 101—88)

This invention relates to numerical printing devices, of the kind having a series of rotatable numbering wheels, representing units, tens, hundreds and so on.

5 At present, in devices of this kind, the several numbering wheels are rotated with a step-by-step motion (in the necessary order, and at the proper relative speeds, for consecutive numbering) by individual pawls acting on ratchet teeth on the 10 wheels. The pawls are customarily mounted on a common carrier oscillated (in synchronism with the successive operations of printing) by a spring-plunger acted on by the platen or equivalent of the printing machine.

15 These known devices are open to a serious objection in that, at times, the pawls do not advance the numbering wheels the exact distance required. As a result, the numbers are printed incorrectly, and a whole sequence of printed 20 sheets or the like may be spoiled.

The object of the present invention is to provide numerical printing devices which will be more reliable than heretofore, even at high printing speeds.

25 According to the invention, I provide numerical printing devices of the kind stated in which the step-by-step motion of the tens, hundreds, and other multiple-unit wheels is effected by inter-engageable teeth or other coupling elements thereon, and in which each said wheel—through the said teeth or elements—is connectible, at, and for, such time as is necessary for its successive step-movements, to the lower multiple (or, in the case of the tens wheel, to the 30 units) wheel adjacent, such units wheel being directly rotated—through pawl-and-ratchet means or otherwise—by, and in synchronism with, the platen or equivalent of the printing machine.

35 More specifically, the invention comprises numerical printing devices of the kind stated in which each numbering wheel has one of its numerals ("9" for forward-numbering, and "0" for backward-numbering devices) formed or carried on a member which is slidable radially in the wheel and has a tooth projecting axially thereof, and in which the tens, hundreds, and other multiple-unit wheels have each a series of fixed teeth projecting towards the radially-slidable tooth adjacent, the units wheel being rotated step-by-step through means operated directly from the platen or equivalent, and each radially-slidable member being moved so as to engage the tooth thereon with one of the fixed 50 teeth adjacent, for the purpose of rotating the

corresponding adjacent wheel through one step-movement.

The radially-slidable member is movable preferably by cam means, which, as the numbering wheel concerned is rotated so as to bring the numeral "9" or "0" (whichever is borne by the said member) into printing position, causes the member to slide upwards to "type level" and the tooth thereon to abut against the uppermost of the fixed teeth adjacent, and which, as soon as the next step-movement of the said numbering wheel is completed, causes the member to be retracted, so as to disengage the said teeth, the corresponding adjacent numbering wheel, in the 15 course of such movement, having been drawn round one step.

The invention, as applied to a numerical printing device of the "backward-numbering" type, will now be described by way of example, with 20 reference to the annexed drawing, in which:

Fig. 1 is a view of the device in longitudinal section, its pawl mechanism being removed;

Fig. 2 is an end-sectional view taken on the line 25 11—11 (Fig. 1) looking in the direction of the arrows;

Fig. 3 is a plan view of the device;

Fig. 4 is an end view of the pawl and ratchet mechanism (looking away from the plunger of the device);

Fig. 5 is a view of the tens numbering wheel, 30 with its fixed teeth and a detent device;

Fig. 6 is a view of the units wheel, looking towards its radially-slidable member and cam;

Fig. 7 is a diagrammatic view of the fixed teeth 35 of the tens numbering wheel and the path of the slidable tooth on the units wheel.

Referring to the drawing:

The device has a frame 1, in which a fixed hollow shaft 2 and a rotatable inner shaft 3 are mounted. At the left-hand end (Fig. 1) of the 40 shaft 3, a crank 4 is formed. With the ball-shaped end 5 of this crank, there engages a slotted dependent lug 6 on a plunger 7. Guides 8 on the latter are slidable in vertical holes 9 in the frame, and a strong spring 10 forces the plunger normally to its upper position, as illustrated. This spring is housed in a cup-shaped recess 11 in the frame 1 and its upper end is centralized against the plunger by a ball-mounted spring-pressed 45 cap 12.

The shaft 3, at its right-hand end (Fig. 1), is formed with a squared portion 13. On this, a carrier 14 (Fig. 4) provided with spring-pressed pawls 15 is secured. These latter engage with a ratchet wheel 16, backward rotation of which is 50 55

prevented at all times by a spring-pressed catch 17.

On the hollow shaft 2, the numbering wheels 18, 19, 20, 21 and 22 are rotatably mounted. 5 These each carry type-numerals "0 to 9" arranged equidistantly round their circumferences (Fig. 3). The respective wheels mentioned denote units, tens, hundreds, thousands and tens of thousands. As will also be seen from Fig. 3, 10 the top of the plunger 7 is formed with type-letters "No".

Each numbering wheel 18 to 22 is provided with a cam disc 23 fixed on the hollow shaft 2. On the face of this disc, a cam slot 24 is formed. 15 The type-numeral "0" of each numbering wheel is carried on a radially-slidable member 25, and a pin 26 thereon engages with the cam slot 24. On the side of the member 25, a tooth 27 is provided (see also Fig. 6); in the case of the numbering wheel 22, such tooth is omitted. A series 20 of teeth 28 is fixed equiangularly round the face of each numbering wheel 19 to 22 directly opposite the respective tooth 27, the disposition of such teeth 28 corresponding to that of the type-numerals aforesaid.

Each numbering wheel 19 to 22 is formed with a decagonal rim 29. Against this, a detent-device 30 (Fig. 5) is pressed by a strong spring 31. The strength of the spring is sufficient to draw the angle of the wheel rim 29 into the V-shaped groove 32, should the wheel have over-reached or stopped short of its precise step-movement.

The modus operandi of the device is as follows:—

35 The frame 1 is mounted in the usual manner on the type-bed (not shown). As a result, the plunger 7 is depressed at each printing operation by the platen or equivalent of the printing machine. By this means, the crank 4 is caused to 40 rock the shaft 3, and the carrier 14 thereon draws back the pawls 15 over the ratchet wheel 16. The extent of backward movement is substantially equivalent to one ratchet tooth, there being ten such teeth in all. As will be apparent, 45 the catch 17 keeps the wheel 16 stationary during this operation.

When the platen or equivalent recedes, and the plunger 7 rises under the action of spring 10, the crank 4 and carrier 14 cause the pawls 15 to 50 force the ratchet wheel 16 round the distance of one tooth, i. e., $\frac{1}{10}$ th of a revolution. In this position, the wheel 16 is held by the catch 17.

Since the ratchet wheel 16 is fixed to the units numbering wheel 18 (see key 33 in Fig. 1), the latter is also stepped forward $\frac{1}{10}$ th of a revolution. 55 This motion takes place each time the plunger 7 is depressed and released.

In practice, movement requires to be transmitted to the tens wheel 19 only when the units wheel 60 18 has printed in succession the type-numerals "9 to 0". Such transmission is effected as follows:—

With the type-numeral "1" uppermost (Fig. 7), the tooth 27 in wheel 18 will be at the position 27^a. On the next step-movement of the units wheel 18, the tooth 27 (under the constraint exercised on the radially-slidable member 25 by the cam slot 24) is raised into abutment against the tooth 28 which is uppermost on the 70 tens wheel 19. In this position, the type-numeral "0" on the units wheel is uppermost, and after printing, it is moved $\frac{1}{10}$ th of a revolution to the left (Fig. 6). In the course of such movement, the tooth 27—through engagement with tooth 28 75 aforesaid—carries the tens wheel 19 round $\frac{1}{10}$ th of

a revolution likewise. At the conclusion of this movement, the tooth 27 (under the constraint of the cam slot 24 on the member 25 of the units wheel) will be just free from the tooth 28 (see 27^b, Fig. 7). As a consequence, on the next step-movement of the units wheel 18, the tens wheel 19 will be left undisturbed.

The same transmission action will take place between the units and tens wheels 18, 19 when the former has printed a further sequence of 10 type numerals "9 to 0". Likewise, when the tens wheel 19 has printed its full sequence of numerals, the type numeral "0" of such wheel (under the constraint of the corresponding cam slot 24) will have been raised, and the relative tooth 27 will 15 be in engagement with the uppermost tooth 28 of the hundreds wheel 20 and—at the next operation of the tens wheels—will carry such wheel 20 round one step. As will be appreciated, the transmission to the remaining wheels 21 and 22 is 20 effected similarly.

Since, in many cases, it is not desired to print with all five numbering wheels 18 to 22 (e. g., when numbering only one thousand pages), it is customary in numerical printing devices to make 25 the type numeral "0" of each wheel manually depressible below type level. In my invention, for this purpose, a notch 34 is provided in each cam slot 24, the pin 26 being depressible into this notch by simply moving the type-numeral "0" 30 slightly beyond its uppermost position and thrusting the radially-slidable member 25 inwards. When the numbering wheels are in normal operation, there is no tendency, it is found, for the pin 26 to drop into the notch 34 accidentally, the 35 tooth 27 on the member 25 being in frictional engagement at that point with the driven tooth 28.

It will be apparent that, since the plunger spring 10, in the case of four or five figure numbers, must supply the power to pull over from time to time a corresponding number of wheels, it should be made particularly strong, and that the strength of the detent springs 31 should be high likewise, though not, of course, so high as 45 that of the spring 10.

Since only a single ratchet wheel 16 is necessary, duplicate pawls 15 can, as illustrated, be conveniently used, for reliability. Moreover, since the periodic coupling of the numbering wheels to 50 one another depends solely on positively operated means, there is little or no danger of failure to rotate each wheel as and whenever required, even at high printing speeds.

I claim:

1. For a printing machine, a numerical printing device comprising a series of rotatable numbering wheels representing units, tens, hundreds and so on; a member radially slidable on each numbering wheel and having thereon one of the terminal numbers of the series on said wheel; a tooth projecting from each member axially of said wheel; a series of fixed teeth projecting from each of said wheels and arranged for engagement by the tooth on the radially slidable member of an adjacent wheel; means for imparting step by step rotation to said units wheel; and means operative to actuate each slidable member radially of its wheel so that the tooth on such member is caused to engage one of the 70 teeth on an adjacent wheel and rotate the latter.

2. For a printing machine, a numerical printing device comprising a series of rotatable numbering wheels representing unit, ten, hundreds and so on; a member radially slidable on each 75

numbering wheel and having thereon one of the terminal numbers of the series on said wheel; a tooth projecting from each member axially of said wheel; a series of fixed teeth projecting from each of said wheels and arranged for engagement by the tooth on the radially slidable member of an adjacent wheel; means for imparting step by step rotation of said units wheel; and cam means operative to cause said slidable member to move radially to type level and engage its tooth with one of the fixed teeth on the adjacent numbering wheel as each numbering wheel is rotated to bring the terminal numeral of its series into printing position, said cam means being constructed and arranged so that when the succeeding one step movement of the numbering is completed the radially slidable member will be retracted and its tooth disengaged from the tooth on said adjacent numbering wheel which will have been rotated through a one step movement during such succeeding step movement of the numbering wheel carrying said member.

3. For a printing machine, a numerical printing device comprising a series of rotatable numbering wheels representing units, tens, hundreds and so on; a radially slidable member carried by said numbering wheels and having thereon one of the terminal numerals of the series of numerals on said wheel; a tooth projecting from each radially slidable member axially of its numbering wheel; a series of fixed teeth projecting from each numbering wheel; means for imparting step by step rotation to the first numbering wheel of said series; and cam means operative to cause the slidable member carried by such wheels to move radially into type level position and engage its tooth with one of the teeth on the adjacent numbering wheel to rotate the latter as each numbering wheel is rotated to bring one of the terminal numerals of the series thereon into printing position, said cam means being constructed and arranged so that said radially slid able member is retracted below type level when slightly offset from printing position and rotation of the adjacent wheel limited to one step.

4. A numerical printing device as claimed in claim 1 comprising decagonal rims on the tens and other multiple unit wheels and spring detent devices having grooved members adapted to engage with the angles of said rims.

5. A numerical printing device as claimed in claim 3 wherein the cam means comprises notched means constructed and arranged so that the radially slidable member is compressible below type level when slightly offset from its printing position.

6. For a printing machine, a numerical printing device comprising a series of rotatable numbering wheels; a member radially slidable on each numbering wheel; a tooth projecting from each member axially of said wheel; a series of fixed teeth projecting from each of said wheels and arranged for engagement by the tooth on the radially slidable member of an adjacent wheel; means for imparting step by step rotation to one of said wheels; and means operative to actuate each slidable member radially of its wheel so that the tooth on such member is caused to engage one of the teeth on an adjacent wheel and rotate the latter.

7. For a printing machine, a numerical printing device comprising a series of rotatable numbering wheels; a member radially slidable on each numbering wheel; a tooth projecting from each member axially of said wheel; a series of fixed teeth projecting from each of said wheels and arranged for engagement by the tooth on the radially slidable member of an adjacent wheel; means for imparting step by step rotation to one of said wheels; and cam means operative to actuate each slidable member radially of its wheel so that the tooth on such member is caused to engage one of the teeth on an adjacent wheel and rotate the latter, said cam means being constructed and arranged so that when the succeeding one step movement of the numbering is completed the radially slidable member will be retracted and its tooth disengaged from the tooth on said adjacent numbering wheel which will have been rotated through a one step movement during such succeeding step movement of the numbering wheel carrying said member.

8. A numerical printing device as claimed in claim 6 wherein decagonal rims are provided on certain of said wheels together with spring detent devices having members adapted to engage with the angles of said rims.

WILLEM GERHARD BRILL. 50
